(57) **CLAIM**

The ornamental design for a display screen support apparatus, as shown and described.

DESCRIPTION

FIG. 1 is a perspective front-side view of the display screen support apparatus of the present invention, with the wheels of the apparatus shown in phantom, the wheels not forming part of the inventive design;

FIG. 2 is a top plan view of the support apparatus of FIG. 1; FIG. 3 is a front elevation view of the support apparatus of FIG. 1;

FIG. 4 is a side elevation view of the support apparatus of FIG. 1, the opposite side being a mirror image of FIG. 4;

FIG. 5 is a rear elevation view of the support apparatus of FIG. 1;

FIG. 6 is a bottom plan view of the support apparatus of FIG. 1; and,

FIG. 7 is a perspective rear-side view of the support apparatus of FIG. 1.
